UNITED STATES PATENT OFFICE.

ERNEST C. HILLMAN, OF LOS ANGELES, CALIFORNIA.

DESIGN FOR A SUN AND RAIN SHIELD.

59,350.

Specification for Design.

Patented Oct. 11, 1921.

Application filed December 27, 1920. Serial No. 433,480. Term of patent 7 years.

To all whom it may concern:

Be it known that I, ERNEST C. HILLMAN, citizen of the United States, residing at Los Angeles, in the county of Los Angeles, State of California, have invented a new, original, and ornamental Design for a Sun and Rain Shield, of which the following is a specification, reference being had to the accompanying drawing, forming a part thereof.

The figure is a perspective view of a sun and rain shield, showing my new design.

I claim:

The ornamental design for a sun and rain shield, as shown.

ERNEST C. HILLMAN.
